UNITED STATES PATENT OFFICE.

WILLIAM O. COLEMAN, OF MEMPHIS, TENNESSEE.

SEED-COTTON SEPARATOR AND CLEANER.

SPECIFICATION forming part of Letters Patent No. 269,387, dated December 19, 1882.

Application filed September 15, 1882. (No model.)

To all whom it may concern:

Be it known that I, WILLIAM O. COLEMAN, of Memphis, in the county of Shelby and State of Tennessee, have invented certain new and useful Improvements in Seed-Cotton Separators and Cleaners; and I do hereby declare the following to be a full, clear, and exact description of the invention, such as will enable others skilled in the art to which it pertains to make and use the same.

My invention relates to an improvement in seed-cotton separators and cleaners, and is designed more especially as an improvement on the seed-cotton separator and cleaner the application papers of which were filed by me September 9, 1882.

In this improved machine the same number of parts are employed and the position of the several parts are the same as those referred to in the previous application; but the peculiar construction of several parts of the present machine is adapted to more thoroughly agitate and separate the seed-cotton from the bolls, twigs, &c., than that shown in the prior application.

In the accompanying drawings, Figure 1 is a longitudinal vertical sectional view of my improved machine. Fig. 2 is a plan view of the stripping cylinder. Fig. 3 is a similar view of the clearing-roller. Fig. 4 is a similar view of the hulling-cylinder. Fig. 5 is a plan view of the feeding-cylinder, and Fig. 6 is a plan view of grating.

A represents the frame of the machine; B, the hopper, through which the seed-cotton with its mixed impurities is fed to the machine by hand or by suitable machinery adapted for the purpose.

D is a series of grate-bars, adjustably secured by their upper extremities to the end of the machine-frame. These grate-bars are made of metal or wood, and are separated sufficiently to allow twigs, dirt, &c., to fall through, but not enough to afford an escape for the seed-cotton. The lower ends of the grate-bars composing the series are secured together by the transverse brace b, which latter prevents the bars from spreading and increasing the space between two or more bars, which would afford an egress for the seed-cotton before being operated upon. These grate-bars, instead of being straight, as shown in my former applica-

tion filed September 9, 1882, are curved for the greater portion of their length, except the upper ends, which rest against and are secured to the board c. The bars, immediately after leaving the board c, curve inward until near the lower ends thereof, and the extreme ends of the bars D are then bent downwardly nearly at right angles to the remaining portions thereof, and the brace b is secured thereon in such a position as not to interfere with the free passage of the cotton downward to the feeding-cylinder. When the cotton, hulls, &c., are deposited into the hopper it descends for a distance before striking the grate-bars, and is then shot by the curvature thereof onto the feeding-cylinder E. When the seed-cotton, with its mixed impurities, strikes the grate-bars a portion of the loose sand and other foreign matters falls through the grate-bars, or is drawn upward through the dust-flue N by the fan O. As before stated, the grating D is made adjustable. This may be accomplished by the use of a rack, a', and toothed pinion b', and is for the purpose of increasing and decreasing the space between it and the feeding-cylinder through which a portion of the loose bolls, twigs, and heavier trash passes from the machine before reaching the feeding-cylinder. 80

The feeding-cylinder E is journaled in movable bearings c', secured by bolts d' and nuts d'' in slots e', which enable the cylinder to be moved nearer to or farther away from the separating-cylinder F, so as to decrease or increase the distance or space between them, as circumstances demand, for the passage of hulls and other impurities. The feeding-cylinder E is provided throughout its entire circumference with longitudinal grooves or furrows d, situated about one inch apart, and are about five-eighths of an inch wide. The cylinder E revolves in the direction of the arrow, and the cotton is more securely held thereby than if the cylinder were perfectly smooth, and at the same time the corners of the ribs e, striking the seed-cotton, loosen the hulls therefrom, and to some extent knock them backward toward the front of the machine and cause them to fall through the opening between the cylinder and grating. The seed-cotton, with the impurities remaining therein, is carried over to the separating-cylinder F, which latter is situated in a plane slightly higher than the

feeding-cylinder. This cylinder F is similar to the one shown and described in application "A," and operates in the same manner. The seed-cotton is taken up by the points of the teeth of this cylinder, and is carried upward thereby until the hulling-cylinder G is reached, which latter is situated over the separating-cylinder. This hulling-cylinder G revolves about six times as fast as the separating-cylinder, and is adapted to knock back all bolls, twigs, &c., that have been carried upward by the saws or teeth of the separating-cylinder. Instead of making the hulling-cylinder G smooth, as shown in application previously referred to, it is provided throughout its periphery with longitudinal grooves f. The spikes h of this cylinder are secured in the ridges or ribs g, and are inclined backward, as shown, and are adapted to work between the saws or teeth of the separating-cylinder and knock back the bolls, twigs, &c., which are exposed to the action of the spikes. The bolls and twigs, together with the adhering seed-cotton that is knocked backward by the hulling-cylinder, falls onto the grating D with considerable force, which loosens the mass and allows the dirt and sand contained therein to either fall through the grating D or be drawn upward through the grating J and forced out through the dust-flue N by means of the fan O. A smooth hulling-cylinder, as shown in my application previously referred to, is liable to let pass any leaves or small pieces of twigs situated directly over the saws or teeth of the separating-cylinder; but with this improved grooved cylinder the ribs g clean the seed-cotton over the saws, while the spikes or nails h remove all the foreign matter from the cotton between the teeth or saws.

As before stated, the hulling-cylinder G is intended to remove all bolls and hulls from the saw-cylinder; but if, instead of knocking them off, they should stick to the teeth of the hulling-cylinder, they would revolve with and choke the said cylinder and impair its usefulness; and to overcome this obstacle I have provided the clearing-roller H, which latter is intended to remove all particles adhering to the teeth of the hulling-cylinder. This clearing-roller is provided with alternating or broken rows of teeth, as shown in Fig. 3, adapted to work between the teeth of the hulling-cylinder and remove all adhering matter therefrom. These teeth are bent backward similarly to those of the hulling-cylinder, and as the cylinder and roller revolve in the same direction the matter removed therefrom by the roller is thrown backward onto the grating.

If any of the foreign particles removed from the hulling-cylinder by the clearing-roller should adhere to the teeth of the clearing-roller, it is removed therefrom by the beveled brace I, to which the grate-bars J are secured. These grate-bars are separated sufficiently to enable dust, sand, and small particles of the separated matter to pass between them, but not wide enough for the passage of the seed-

cotton or hulls, and are situated over the inner opening of the dust-flue N and partly under the fan O. This fan is geared with the other mechanism and creates an upward draft, by means of which the lighter particles of foreign matter are discharged from the machine. The seed-cotton that has been knocked back onto the grating D by the hulling-cylinder G and the clearing-roller H mixes with the seed-cotton on the grating and goes through the same operation until all the bolls, twigs, &c., have been removed therefrom. During these different movements the cotton is torn apart and loosened, which frees all the dirt and allows it to fall onto the grating or be drawn upward by the air-blast before referred to. The cotton that adheres to the teeth of the separating-cylinder during its operation and passes beyond the hulling-cylinder is carried by the said separating-cylinder around to the stripping-cylinder K, which latter runs faster than the separating-cylinder. This stripping-cylinder is made of wood, and is provided with alternating or broken rows of teeth, as shown in Fig. 2. A wire screen is situated immediately under this cylinder, and the cotton, as it is torn from the teeth of the saws, is carried over this screen L by the teeth of the stripping-cylinder. The cylinder K revolves in an opposite direction from that of the separating-cylinder, and moves about four times as fast, and as the cotton is brought around by the cylinder F it is removed therefrom by the teeth of the cylinder K, which work between the teeth of the separating-cylinder.

When the rows of pins or teeth of the cylinder K are continuous or unbroken, as in my previous application, they are inclined to move the cotton over the screen L without agitating it or changing its position; but when the rows are broken or the teeth arranged alternately, as shown, the cotton is loosened and torn apart, which frees what sand or dirt remains therein and allows it to fall through the screen. The cotton is carried upward by this stripping-cylinder until the delivery-spout M is reached, onto which the thoroughly cleaned and separated seed-cotton passes, and is discharged therefrom and falls in a loose pile on the floor or into any receptacle prepared to receive it; or the machine can be set on a floor above a gin, and by suitable guides, chutes, or conveyors deliver the seed-cotton into the gin; or it can be set below a gin, and by means of an elevator deliver up and discharge the cotton into it.

The small clearing-roller H is merely intended to keep any cotton or hulls from making a complete revolution on the hulling-cylinder, and the beveled brace I is intended to prevent the same from taking place on the clearing-roller.

My invention is simple in construction, is durable in use, and effectually cleans the cotton of all impurities before ginning.

It is evident that slight changes and alterations in the construction and relative arrange-

ment of the different parts might be resorted to without departing from the spirit of my invention; and hence I would have it understood that I do not limit myself to the exact construction shown and described, but consider myself at liberty to make such changes and alterations as come within the spirit and scope of my invention.

Having fully described my invention, what I claim as new, and desire to secure by Letters Patent, is—

1. In a machine for cleaning seed-cotton, the combination, with a receiving-hopper and a feeding-cylinder, of curved grate-bars, the upper ends of which are pivotally secured to the machine-frame, and means for adjusting the said grate-bars, whereby the space between the lower ends thereof and the feeding-cylinder is increased or diminished, substantially as set forth.

2. In a machine for cleaning seed-cotton, the combination, with the receiving-hopper and curved adjustable grate-bars, of a feed-cylinder provided throughout its periphery with longitudinal slots to form ribs, substantially as set forth.

3. In a machine for cleaning seed-cotton, the combination, with a suitable hopper, a feeding-cylinder, and a separating-cylinder, the former being supported on movable bearings, of a series of curved grate-bars situated under the hopper and adapted to deliver the seed-cotton to the feeding-cylinder, the said grate-bars being pivoted at their upper ends to the frame of the machine and provided at their lower ends with adjusting devices, whereby the space between the grate-bars and feeding-cylinder is increased or diminished, substantially as set forth.

4. The combination, with the feeding-cylin-

der, provided with longitudinal slots, and the separating-cylinder, situated in a plane slightly higher than the feeding-cylinder, of the hulling-cylinder, situated above the toothed separating-cylinder and provided with longitudinal slots or grooves and teeth, all of the above parts adapted to operate as described.

5. The combination, with the separating-cylinder and the grooved hulling-cylinder situated above the same, and provided with spikes or teeth, of the clearing-roller situated above and to one side of the hulling-cylinder, and provided with alternately arranged teeth adapted to work between the teeth of the hulling-cylinder, substantially as and for the purpose set forth.

6. The combination, with the separating and hulling cylinders, of the clearing-roller and beveled brace I, all of the above parts constructed, combined, and adapted to operate as described.

7. The combination, with the grating D, brace I, and grating J, of the mechanism for cleaning and separating the seed-cotton, and the fan O, all said parts being combined and adapted to operate substantially as set forth.

8. The combination, with the grating D, cylinders E, F, and G, roller H, brace I, grating J, fan O, and flue N, of the cylinder K, wire screen L, and spout M, all of the above parts constructed, combined, and adapted to operate as described.

In testimony whereof I have signed this specification in the presence of two subscribing witnesses.
